UNITED STATES PATENT OFFICE.

GEORGE A. KOHOUT, OF CHICAGO, ILLINOIS, ASSIGNOR TO COKAL STOKER CORPORATION, OF CHICAGO, ILLINOIS, A CORPORATION OF ILLINOIS.

STOKER.

1,355,095.

Specification of Letters Patent.

Patented Oct. 5, 1920.

Application filed May 27, 1918. Serial No. 236,742.

To all whom it may concern:

Be it known that I, GEORGE A. KOHOUT, a citizen of the United States, residing at Chicago, in the county of Cook and State of Illinois, have invented a certain new and useful Improvement in Stokers, of which the following is a full, clear, concise, and exact description, reference being had to the accompanying drawings, forming a part of this specification.

My invention relates to stokers or stoking grates and has for its object the provision of an improved form of structure of this nature in which by means of operating the structure the fuel is progressively moved toward the rear over the grate so that the green fuel when originally introduced is coked and is thereafter progressively moved over the grate so that the coke or other remaining product may be properly consumed. The green fuel is preferably introduced at one extremity only so that the gases and volatile products given off during the coking process may be properly consumed by passing over a hot fire bed in their progress toward the chimney or stack. If for any reason the fuel is placed unevenly on the stoker or if blow holes occur or are formed, the stoker moves the coal longitudinally and also laterally to even the coal bed and to fill up the blow holes. This lateral movement of the coal occurs in a manner later to be described.

In the preferred form of my invention the stoker sections are so arranged that the act of shaking them causes this progressive movement of the fuel thereover toward the rear of the furnace.

I will explain one form which my invention may take more in detail by reference to the accompanying drawings, in which—

Figure 1 is a vertical sectional view of a grate structure of my invention shown in connection with a fragmentary portion of a furnace or boiler;

Fig. 2 is a top portion of the grate stoker, certain furnace parts being shown in section;

Fig. 3 is a sectional view on line 3—3 of Fig. 1;

Fig. 4 is a fragmentary perspective of the bearings for the stoker bars;

Fig. 5 is a view showing the coöperating cover plates or locking clips for the bearings aforesaid;

Fig. 6 is a sectional view on line 6—6 of Fig. 1;

Fig. 7 is a sectional view on line 7—7 of Fig. 6;

Fig. 8 is a fragmentary enlarged view of 60 the stoker structure of Fig. 1 in its tilted condition;

Fig. 9 is a fragmentary perspective of one of the stoker bar sections;

Fig. 10 is a fragmentary view showing a 65 modified form of end dumping arrangement, and

Fig. 11 is a sectional view on line 11—11 of Fig. 8.

In the drawings I show a furnace having 70 the front wall 11, boiler 12, firing door 13 and passageway 14 to the stack or tubes. My improved stoker consists of a plurality of preferably intermeshing sections 15, 16. The structure of these grate sections will be 75 more clearly apparent from an inspection of Figs. 8 and 9. Each stoker bar section is provided at its opposite extremities with trunnions 17 and is also provided with a downwardly extending arm 18. The trunnions 17 are located centrally on the stoker bar sections, that is, between the edges of the sections. This location of the trunnions provides balanced bar sections which are easy to operate, for while the portions *a* 85 (see Fig. 2) are being moved upwardly against the weight of the fuel, the portions *b* are moving downwardly, assisted in such movement by the weight of the fuel resting thereon. I thus provide a stoker which can 90 be tilted more easily than those now on the market. The arms 18 are all connected pivotally at their extremities to a shaking bar 19, which is actuated by the link 20 controlled by the lever 21. This lever is pivotally mounted upon the link 22 secured to the front of the furnace and is provided with a handle 23 so that it may be actuated from the full line position shown in Fig. 1 to the dotted line position shown in the same 100 figure. A dog 24 coöperating with a pin 25^a normally holds the lever 21 in its neutral position.

The stoker bar sections in general have the construction shown more clearly in Figs. 105 9 and 10. These sections, as shown, are hollow, having at their top portions the perforated face plates 25. Downwardly extending aprons or skirts 26 form parts of the stoker structure, the purpose of which will 110

be more clearly apparent hereinafter. The stoker bar sections have wider and narrower portions, as shown, so that these staggered protruding portions may intermesh, as shown more clearly in Fig. 2 to provide a smooth perforated air-cooled upper surface. The portions are made wider and narrower so that when the stoker bar sections are tilted the wider portions will project above the narrower portions, as is shown in Fig. 8, and will loosen and break up any clinkers and stir up the ashes. These wider and narrower portions also coöperate to advance the fuel along the bed and spread it on the bed to fill up any blow holes. Normally the top surfaces of the sections lie in the same plane. This plane may be horizontal as shown in Fig. 1, or downwardly inclined toward the rear as is usual in furnaces of this kind. When the stoker bars are tilted, the wider portions *a*, (see Fig. 2) projecting toward the front portion of the furnace, are raised above and the rearwardly extending portions *b* are lowered below the plane of the grate as shown in Fig. 8 and in dotted lines in Fig. 1. When thus tilted, the portions *a* break up any clinkers that may have formed, and clinkers and ashes fall into the V-shaped spaces between the aprons 26 and 27 and the adjacent face portions 25. There will be narrow openings at the bottom of the V-shaped spaces through which fine ashes will fall, but it is the purpose of this stoker not to drop the ashes through between the bars. The spaces between the bars are uniform at all times whether the bars are in normal position or are tilted as shown in Fig. 8. The space also remains uniform during the tilting of the bars. The spaces between the bars are approximately one-fourth of an inch in actual practice. When the stoker bar sections are returned to normal position, the portions *b* return along the aprons 27 and raise any clinkers or ashes between the faces 25 and the aprons 27 to the normal plane of the stoker surface. Such clinkers and ashes thus tumble over onto the portions *a* and in the next operation of the stoker are moved upwardly and forwardly by the portions *a*. It is this tumbling over to the sides that causes the fuel bed to be leveled and all blow holes to be filled up. During these movements of the stoker bars, the aprons 26 closely follow the edges 40 and prevent everything but a little fine ashes from falling through. In this manner the fuel is worked rearward in the furnace and the clinkers can be discharged at the end section 42. The portions of the sections of smaller width have the depending aprons 27. The stoker bar shown at the left in Figs. 1 and 8 has a straight edge adjacent the door 18, provided with a depending apron 26^a. This apron is concentric with the pivot 17 in order that the apron may at all times lie close to the forward fixed edge of the furnace to prevent undue dropping through of the fuel. The aprons 26 coöperate with side walls 28 on both sides thereof to form a sort of pocket, there being an end wall 29 at the extremities of the sections. The stoker bar sections are open at the bottom, as clearly apparent, excepting for the partial closure due to the aprons 26 and 27. The trunnions 17 of the sections are carried in structures more clearly shown in Figs. 3, 4, 5 and 7. These structures comprise the side frames 30 suitably mounted in place which have at their top the pillow blocks 31. These pillow blocks 31 receive the trunnions 17. In order to hold the trunnions in position so that they cannot be lifted out upwardly, I provide lugs 32, which lugs coöperate with cover or locking blocks or clips 33, more clearly shown in Fig. 5. These blocks or clips 33 have openings 34 to encircle the trunnions and have cutaway portions 35, 35 which coöperate with the lugs 32, thus to prevent lifting the stoker bar sections out of position when the cover blocks or clips 33 are mounted in place. Fingers 36 are provided which limit the inward movement of the cover blocks or clips 33, these fingers 36 coming into position below the ridge 37 (Fig. 4). The upper portions of the blocks or clips 33 are flattened by having the grooves or openings 38, as clearly apparent from Fig. 5. The positions of the trunnions 17 relative to the stoker bar sections is seen more clearly from an inspection of Fig. 8. The cover blocks or clips 33 are prevented from moving away from the frames 30 by bars 50 on each side of the grate. These bars are provided with lugs 51 on each side, which lugs engage the masonry 52 on one side and the cover blocks or clips 33 on the other. The ends of the bars rest upon the end supports for the stoker frame shown in Fig. 1. When it is desired to remove the stoker bar sections, the bars 50 are first removed by lifting them vertically. The cover clips 33 may be moved laterally of the grate so as to disengage the lugs 32 and then lifted vertically. During the lateral movement of the cover blocks or clips 33, the pivots disengage the openings 34, as will be apparent. The removal of the cover blocks or clips leaves the stoker bar sections free to be lifted out of the blocks 31. The curvature given to the aprons 26 and 27 is such that the axis of the trunnion 17 is eccentrically located relatively to the center point of the circle forming the aprons 26 and 27. In this manner I am enabled to maintain the edges 39 of the wider portions of the stoker bar sections closely contiguous to the apron 27 during the time that the sections are moved from the position shown in Fig. 1 in full lines to the position shown in Fig. 8. Simi-

larly, the edges 40 of the narrower portions of the stoker bar sections remain closely contiguous to the aprons 26, so that at no time during the shaking operation is a large 5 space provided between adjoining sections, but on the contrary, the opening between them is maintained substantially constant. Of course, there is no particular reason for maintaining this opening absolutely constant, but in the particular form of the 10 structure herein disclosed, it is desirable that the opening be of such a size that nothing but burnt out ash may fall downwardly between the sections in about the same manner 15 that this ash would fall through the openings 41, provided in the face plates of the sections.

At the extreme right hand section of Fig. 1, I show an end grate section 42 which is 20 stationary, having openings 41 however, similar to the openings provided in the other sections, and this end section 42 has a rounded inner face 43 so that the immediately adjoining stoker bar sections may be 25 tilted properly without providing a large opening between the stoker bar section and this end section 42 at such times when the stoker bar sections are not dumped farther than a predetermined amount, which in the 30 construction herein shown is approximately 45°. If the sections are dumped to a position of 90°, as shown in Fig. 8, or in Fig. 1 in dotted lines, then quite a substantial opening is occasioned between the end section 35 42 and its immediately adjoining movable stoker bar section. The clinkers and ash are dumped therethrough into the ash pit. Normally, when shaking, the lever 21 is operated to tilt the stoker bars angularly 40 through a distance of about 45°.

It will be understood, of course, that the stoker bar sections are to be tilted only in a clockwise direction from the position they 45 occupy in Fig. 1 in full lines. As these sections during the shaking operation are tilted 45°, the action of each section is to pile up the fuel upon the section immediately to the right (Fig. 1). In this way the fuel is constantly moved from left to 50 right as the lever 21 is moved back and forth. The result of this actuation is that the green fuel which is thrown in through the firing door 13 is thrown upon the sections farthest to the left. Then this green 55 fuel may be coked, the products of combustion passing over the hot fuel bed farther to the right, there to be consumed before passing to the stack. A subsequent actuation of the lever 21 causes a movement 60 of the entire fuel bed to the right, thus providing space for additional green fuel.

Whenever it is desired to remove the clinkers or other residue which has not 65 passed through the stoker bar sections, then the lever 21 is actuated to tilt the

sections more than 45° so that an opening is provided at the extreme right hand portion of the grate immediately to the left of the end section 42. If this dumping has been sufficient to permit an open space 70 on top of the movable section at the extreme right (Fig. 1), then thereafter the lever 21 is actuated to tilt the stoker bar sections a number of times through an angle of 45°, whereby the fuel is moved progressively to 75 the right to cover any such open space.

It will be noted that the arrangement is such that a conjoint movement of all of the sections causes this progressive movement of the fuel. Not only does the shaking of 80 the stoker sections cause a progressive movement of the fuel toward the rear of the furnace, but it also levels the fuel bed, thus insuring a more efficient combustion of the fuel.

In Fig. 10, I show a modified form of end section which is to take the place of the end section 42, when desired, and this end section 44 is pivotally mounted, as shown at 45 so that it may be tilted when the link 46 is actuated back and forth, as will be 90 readily apparent. I find that under certain circumstances it is better to actually tilt the end section than to depend merely on the opening between the last movable stoker 95 section, such as the section 42.

From what has been described the nature of my invention will be readily clear to those skilled in the art, and it will also be apparent that many modifications may 100 be made within the scope of the appended claims.

Having, however, thus described one form which my invention may take, what I claim as new and desire to secure by Letters Patent is:

1. A stoker having a plurality of individual intermeshing pivoted sections arranged in a series and having their top surfaces arranged substantially in a plane, means for conjointly tilting all of said sections, each section having means adapted when said section is tilted to deposit fuel upon the next succeeding section of the series, and means provided upon each section eccentric to the 115 pivot thereof for preventing dumping of the fuel through adjoining tilted grate sections.

2. A stoker having a plurality of individual sections arranged in a series and having their top surfaces arranged substantially in 120 a plane, means for simultaneously tilting all of said sections, each section having projecting portions which intermesh with portions of adjoining sections and means adapted when said section is tilted to deposit fuel 125 upon the next succeeding section of the series, and non-concentric aprons on each section for preventing dumping of the fuel through adjoining tilted grate sections.

3. A stoker having a plurality of individ- 130

ual intermeshing sections arranged in a series and having their top surfaces arranged substantially in a plane, means for conjointly tilting all of said sections, each section having means adapted when said section is tilted to deposit fuel upon the next succeeding section of the series, means provided upon each section for preventing dumping of the fuel through adjoining tilted grate sections, and a normally stationary end section having means for preventing dumping of the fuel between said end section and its adjoining movable section when said movable section is tilted a given amount, but permitting dumping of the fuel when said adjoining movable section is tilted a given amount.

4. A stoker having a plurality of individual sections arranged in a series, and having their top surfaces arranged substantially in a plane, means for simultaneously tilting all of said sections, each section having means adapted when said section is tilted to deposit fuel rearwardly and sidewardly upon the next succeeding section of the series, means on each section for preventing dumping of the fuel through adjoining tilted grate sections, and a normally stationary end section having means for preventing dumping of the fuel between said end section and its adjoining movable section when said movable section is tilted a given amount, but permitting dumping of the fuel when said adjoining movable section is tilted a given amount.

5. A stoker having a plurality of individual sections arranged in a series, and having their top surfaces arranged substantially in a plane, means for conjointly tilting all of said sections, each section having means adapted when said section is tilted to deposit fuel upon the next succeeding section of the series, means provided upon each section for preventing dumping of the fuel through adjoining tilted grate sections, and a normally stationary end section having means for preventing dumping of the fuel between said end section and its adjoining movable section when said movable section is tilted a given amount but permitting dumping of the fuel when said adjoining movable section is tilted a given amount, and means for at will tilting said end section.

6. A stoker having a plurality of individual sections arranged in a series and having their top surfaces arranged substantially in a plane, means for simultaneously tilting all of said sections, each section having projecting portions which intermesh with portions of adjoining sections and means adapted when said section is tilted to deposit fuel upon the next succeeding section of the series, means eccentric to the pivots of the section for preventing dumping of the fuel

through adjoining tilted grate sections, a normally stationary end section having means for preventing dumping of the fuel between said end section and its adjoining movable section when said movable section is tilted a given amount, but permitting dumping of the fuel when said adjoining movable section is tilted a given amount, and means for at will tilting said end section.

7. A stoker having a plurality of intermeshing individual pivoted sections arranged in a series and having their top surfaces arranged substantially in a plane, means for conjointly tilting all of said sections, each section having wide portions coöoperating with narrow portions on adjoining sections and said wide portions being adapted when said section is tilted to deposit fuel upon the next succeeding section of the series, and means provided upon each section eccentric to its pivot for preventing dumping of the fuel through adjoining tilted sections.

8. A stoker having a plurality of intermeshing individual pivoted sections arranged in a series and having their top surfaces arranged substantially in a plane, means for simultaneously tilting all of said sections, each section having means adapted when said section is tilted to deposit fuel rearward and sidewardly upon the next succeeding section of the series, and means for preventing dumping of the fuel through adjoining tilted sections, said last named means comprising depending aprons eccentric to the pivots of the sections.

9. A stoker having a plurality of individual balanced sections arranged in a series and having their top surfaces arranged substantially in a plane, means for conjointly tilting all of said sections, each section having means adapted when said section is tilted to deposit fuel upon the next succeeding section of the series, depending eccentric aprons provided upon each section for preventing dumping of the fuel through adjoining tilted sections, and means for tiltily supporting said individual sections, said aprons maintaining a constant space between the adjacent edges of the several sections when the sections are tilted.

10. A stoker having a plurality of individual sections arranged in a series and having their top surfaces arranged substantially in a plane, means for simultaneously tilting all of said sections, each section having wide portions which swing below the normal plane of the section top when the section is tilted and permitting the fuel to be lowered therewith and adapted, when said section is returned, to deposit fuel rearwardly and sidewardly upon the next succeeding section of the series, means for pre-

- venting dumping of the fuel through adjoining tilted sections, and means for tiltingly supporting said individual sections.
11. A stoker having a plurality of centrally pivoted sections arranged in a series and having their top surface arranged substantially in a plane, means for conjointly tilting all of said sections, each section having means adapted when said section is tilted to deposit fuel upon the next succeeding section of the series, removable locking blocks for holding the sections in place, means to permit removal of said blocks, and means provided upon each section for preventing dumping of the fuel through adjoining tilted sections, said last aforesaid means including curved aprons depending from said sections.
12. A stoker having a plurality of individual sections arranged in a series and having their top surfaces arranged substantially in a plane, means for conjointly tilting all of said sections, each section having projecting portions which intermesh with portions of adjoining sections and means adapted when said section is tilted to deposit fuel upon the next succeeding section of the series, and means provided upon each section for preventing dumping of the fuel through adjoining tilted sections, said last aforesaid means including curved aprons depending from said sections, said curved aprons having a curvature non-concentric with the axis of tilting of said sections.
13. A stoker having a plurality of individual sections arranged in a series and having their top surfaces arranged substantially in a plane, means for simultaneously tilting all of said sections, each section having wide portions coöoperating with narrow portions on adjoining sections and means adapted when said section is tilted to deposit fuel upon the next succeeding section of the series, and means for preventing dumping of the fuel through adjoining tilted sections, said last aforesaid means including curved aprons depending from said sections, said curved aprons having a curvature non-concentric with the axis of tilting of said sections.
14. A stoker having a plurality of individual centrally pivoted sections arranged in a series, means for conjointly tilting all of said sections, each section having means adapted when said section is tilted to deposit fuel upon the next succeeding section of the series, and means provided upon each section for preventing dumping of the fuel through adjoining tilted sections, said last aforesaid means including aprons having a curvature eccentric to the axis of rotation of said pivoted sections so as to maintain a constant space between the adjacent edges of the several sections when they are tilted.
15. A stoker having a plurality of individual pivotal sections formed with flat upper surfaces and depending aprons on one side of and non-concentric to the pivots of the sections, pivots for said sections located below and between the extreme edges of said surfaces and means whereby said sections may be operated in unison.
16. A stoker having a plurality of individual sections each provided with wide and narrow portions adapted to intermesh with narrow and wide portions of adjoining sections, pivots for said sections located between the outer edges of said wider portions and means for simultaneously operating all of said sections, said wide portions adapted to lower portions of the fuel below the normal surface of the sections and thereafter raise said fuel portions and deposit them on the adjoining sections.
17. A stoker having a plurality of individual intermeshing pivoted sections, pivots for said sections located between the lateral edges of said sections so as to provide balanced grate sections adapted to lower the fuel and then deposit it on advance sections, and means for simultaneously operating all of said sections.
18. A stoker having a plurality of individual sections, pivots at the ends of the sections, side frames having bearings for said pivots, a ridge on each frame below the bearings, locking clips having openings to receive the pivots and fingers on the locking clips for engaging beneath said ridges to limit the inward movement of the clips.
19. A stoker having a plurality of individual sections, pivots at the ends of the sections, side frames having blocks to receive the pivots and lugs adjacent the blocks, locking clips having portions overlying said pivots and cut away portions to receive said lugs and means to prevent said lugs from disengaging said cut away portions.
20. A stoker having a plurality of individual sections, pivots at the ends of said sections, side frames having blocks to receive the pivots and lugs adjacent the blocks, locking clips overlying said blocks and having cut away portions to receive said lugs and fingers on said clips for engaging the side frames to limit the inward movement of the clips on the frames.
21. A stoker of the character described comprising intermediately pivoted stoker bars, means to operate all of said bars simultaneously to advance the fuel, and aprons depending from the bars and eccentric to the pivots thereof to prevent fuel falling between the bars when they are tilted.
22. A stoker of the character described comprising pivoted stoker bars having inter-

meshing portions, means to operate all of said bars simultaneously to advance the fuel, and aprons depending from the bars and eccentric to the pivots thereof to prevent fuel falling between the bars when they are tilted.

23. A stoker of the character described comprising pivoted stoker bars, means to tilt said bars a certain amount to advance the 10 fuel, said means being adapted to tilt the bars further to permit any refuse to be discharged over the end bar only, and aprons depending from said bars and eccentric to the pivots thereof to prevent discharge of 15 fuel or clinkers between said bars.

24. A stoker of the character described comprising pivoted stoker bars, means to tilt all of said bars simultaneously to advance the fuel, means to dump any clinkers 20 that may collect at the discharge end of the bars, and means eccentric to the pivots of said bars for preventing fuel or clinkers dropping between the bars.

25. A stoker of the character described comprising pivoted stoker bars, an end section adjacent the rear stoker bar, and means to tilt the bars 45° to agitate the fuel and move it forwardly over the bars, said 25 means being adapted to tilt the bars 90° so as to discharge clinkers only between the end section and the rear stoker bar.

26. A stoker of the character described comprising intermeshing stoker bars, an end section adjacent the rear stoker bar, and 30 means to tilt the bars a certain amount to agitate the fuel and move it rearward over the bars, said means being adapted to tilt 35

the bars a further amount so as to discharge clinkers only at the end section.

27. A stoker of the character described 40 comprising pivoted stoker bars having extending portions which move upwardly when the bars are tilted to break up clinkers, agitate the fuel and move it forwardly over the bars, a single lever adapted to tilt all 45 of the bars a certain amount in one direction only, and an end section adjacent the rear stoker bar, said end section having an edge adapted to accommodate the stoker bar and said lever being adapted to tilt the bars 50 a further amount to discharge clinkers and waste fuel between the rear stoker bar and said end section.

28. A stoker of the character described comprising pivoted stoker bars placed edge 55 to edge, pivots for said bars positioned between the edges of the bars and means to prevent fuel and ashes from falling between the bars when they are tilted, said means comprising an apron depending from each 60 bar and eccentric to the pivots of said bar.

29. A device of the character described comprising pivoted stoker bars arranged edge to edge, intermediately located pivots 65 for said bars, and means on said bars eccentric to the pivots thereof for maintaining a constant space between the adjacent edges of two bars when they are tilted to thereby prevent fuel and ashes from falling 70 between the bars.

In witness whereof I hereunto subscribe my name this 11th day of May, A. D. 1918.

GEORGE A. KOHOUT.
